UNITED STATES PATENT OFFICE.

ALEXANDER GILCHRIST HATCH, OF HONOLULU, TERRITORY OF HAWAII, ASSIGNOR,
BY DIRECT AND MESNE ASSIGNMENTS, TO W-H KEYLESS LOCK COMPANY, LIMITED.

CASING FOR KEYLESS LOCKS.

Application filed March 20, 1924. Serial No. 700,686.

To all whom it may concern:

Be it known that I, ALEXANDER GILCHRIST HATCH, a citizen of the United States, residing at Honolulu, Territory of Hawaii, have invented certain new and useful Improvements in Casings for Keyless Locks, of which the following is a specification.

This invention relates to locks, and more especially to a lock of the so-called keyless 10 or permutation type, and has for one of its objects to provide a device of this character which is so constructed that it will be substantially impossible for it to be tampered with through the opening of the casing of the lock, whereby access may be gained to the interior mechanism to the end that the lock might be rendered ineffective thereby.

A further object of the invention is to provide a lock which is enclosed within a 20 casing comprising two or more separable parts, whereby assembly and disassembly of the operative portions may be readily effected by authorized persons, while at the same time the said casing parts are effectively interlocked when the mechanism is assembled so as to make it practically impossible for them to be separated by unauthorized persons.

With the above and other objects in view 30 which will appear as the description proceeds, the invention consists in the novel details of construction and combinations and arrangements of parts more fully hereinafter described and particularly pointed out in the appended claims.

Referring to the accompanying drawings forming a part of this specification in which like reference characters designate like parts in all the views:

40 Figure 1 is a front elevational view of a lock constructed in accordance with the present invention, as applied to controlling the ignition and lighting switches of an automobile, only so much of the actual lock mechanism being shown, however, as is essential to an understanding of the invention;

Fig. 2 is a central vertical sectional view of the parts shown in Fig. 1;

50 Fig. 3 is a vertical cross sectional view of the parts shown in Fig. 2, taken approximately on the plane indicated by the line 3-3 of the said figure, looking in the direction of the arrows;

Figs. 4 and 5 are detail perspective views 55 of the two members of the lock casing;

Fig. 6 is a vertical sectional view through a somewhat modified form of the invention;

Fig. 7 is a transverse sectional view, taken approximately on the plane indicated by 60 the line 7-7 of Fig. 6; and,

Fig. 8 is a horizontal sectional view taken approximately on the plane indicated by the line 8-8 of Fig. 6.

Referring more particularly to Figs. 1 65 to 5 of the said drawings, the numerals 10 and 11 indicate respectively the two members of the lock casing, the former of which is provided with a substantially semi-cylindrical top portion 12 and a back wall 13, 70 which wall is provided with a substantially cylindrical opening 14 to accommodate a suitable disc or plate of insulating material, upon which may be mounted the binding posts and certain parts of the electrical 75 switches for controlling the circuits of the vehicle, which switches may be in turn controlled by the locking mechanism in a manner similar to that described in the prior Patent No. 1,873,283, granted March 29, 80 1921, to Meade Wildrick, and entitled Keyless locks.

The said member 10 is also provided with the downwardly extending front wall 16, 85 having the bore 17 for the reception of a locking bolt 18, which bolt is provided with the downwardly depending legs 19, having the angularly disposed toes 20, which are adapted to enter grooves 21 formed on the side faces of the permutation wheels 22 by providing the said faces with the annular ribs 23, in a manner similar to that disclosed in my pending application, filed March 12, 1924, Ser. No. 698,718, entitled 90 Keyless lock.

The other casing member 11 is shaped substantially, as shown in Fig. 5, and provided with the side walls, 25 and 26, and the front wall 27, which latter is cut away 100 as at 28 to receive the downwardly extending lug 29 of the upper front wall member 16, as will be readily understood from the drawings.

The under edges of the semi-cylindrical top wall member 12 are provided with suitable dove-tail grooves 30, which are adapted to receive the dove-tail tongues 31, which are formed upon the upper edges of the

side walls 25 and 26 of the lower member 11, whereby a sliding engagement between the two members may be had in a horizontal direction, while a relative vertical movement between the two will be prevented.

The permutation wheels 22 are rotatably mounted upon a shaft 33, the ends of which may be received in suitable holes or apertures 34 formed in the side walls 25 and 26 of the member 11, or if desired, the said shaft may be mounted in a separate bearing block carried within the member 11. When mounted in the walls, 25 and 26, as here shown, the said shaft may be provided with suitable collars 35, secured to the said shaft as by the set screws 36, whereby longitudinal displacement of the shaft may be prevented.

The two parts of the casing, 10 and 11, may be secured together, if desired, by means of suitable screws or other fastenings 37, although in some instances it may be desired to omit such fastenings and depend entirely upon the inter-locking of the two members through the co-action of the locking bolt 18 and the permutation discs 22 to maintain the parts in a closed relation.

As described in my said co-pending application and clearly shown in Fig. 2 of the present drawings, the annular ribs 23 are cut away as indicated at 38 to provide passageways through which the toes 20 of the legs 19 may pass from within the said ribs to the outside of the same in order that the parts may be unlocked. It will be clear from Fig. 2 in particular that if the locking bolt is in the position shown therein and the wheels such as 22 be rotated to move the passage 38 out of alignment with the toe 20, that the bolt 18 cannot be moved axially of itself, and that therefore the parts will be efficiently interlocked, since any attempt to slide the lower member 11 relative to the upper member 12, will cause the said member 11 to carry with it the permutation discs or wheels, which movement will bring the inner periphery of the ribs 23 into engagement with the toes 20 of the bolt 18. On the other hand, if the wheels are so set as to bring all of the passages 38 into alignment with the respective toes 20 of the bolt, then such movement will not be prevented, as the toes will pass through the passages 38 of the grooves 21 to the outside of the ribs 23 and the lower part of the casing may be completely disengaged from the upper part in order to gain access to the interior mechanism. This, however, cannot be accomplished unless the permutation discs are set at the predetermined combination, as will be readily apparent.

In Figs. 6, 7 and 8, I have shown a somewhat modified form of the invention wherein the sliding bolt is mounted for substantially vertical movement in a plane at right

angles to the axis of the permutation discs or wheels. This construction is similar to that disclosed in my said co-pending application No. 698,718, the said bolt being designated by the reference character 40.

As best shown in Fig. 7, the said bolt is provided with the downwardly depending legs 41, certain of which are provided with the laterally projecting toes 42, corresponding to the toes 20 of the bolt 18 above described and adapted to co-act with the annular flange or rib 23 of the permutation wheels, to effect the locking of the parts. The said bolt is reciprocated by means of the shaft 44, which carries at one end the fingerpiece 45, and at the other end the operating member 46, provided with the slot 47 which receives the pin 48, carried by the bolt 40, all as is clearly set forth in my said co-pending application.

The side walls 25 and 26 of the lower casing member 11 are provided with the rigid inwardly extending lugs 50 and 51, best shown in Figs. 7 and 8, which are so positioned as to co-act with the outside depending legs 41 of the bolt or slide 40, as to prevent relative sliding movements of the lower casing member 11 when the bolt 40 is in its lower or locked position. However, the parts are so designed and constructed that when the bolt 40 is raised to its unlocked position, the depending legs 41 will be raised above the top edge of the lugs 50 and 51 so that, if desired, the lower casing member 11 may then be pulled outwardly or toward the right, as viewed in Fig. 6, whereby access may be gained to the interior of the lock for repairs or for other purposes.

It will be noted, however, that the members 10 and 11 may only be separated after the proper combination has been set on the permutation wheels and the locking bolt 40 raised, since when the said bolt is in its lower or locked position, sliding movement of the member 11 relative to the member 10 will be prevented, due to the contact of the forward faces of the lugs 50 and 51 against the depending legs 41 of the slide 40.

As above stated, only so much of the locking and switch mechanism as is essential to the understanding of the present invention, has been here illustrated, and in fact the invention might be readily applied to various other forms of locking mechanisms by making slight changes in the construction.

It is therefore obvious that those skilled in the art may vary the details of construction as well as the arrangement of parts without departing from the spirit of the invention, and it is not wished to be limited to the above disclosure except as may be required by the accompanying claims.

What is claimed is:

1. In a lock, a casing member comprising

a back wall and a top portion having dovetail grooves; a second casing member comprising front, bottom and side walls, the latter being provided with complementary 5 tongues for engaging said grooves; and a lock member carried by each of said casing members, said lock members being adapted when engaged to prevent relative movement of said casing members.

10 2. In a lock, a two part casing, the parts being separable by movement in one direction only; one of said parts being provided with a projection; a slidable member carried by the other of said parts, adapted to control 15 the mechanism to be locked, a portion of said member being movable to a co-operative position with said projection to prevent

the separation of said casing parts; and means for controlling the sliding movements of said member.

20 3. In a lock, a two part casing, the parts being separable by movement in one direction only; one of said parts being provided with an integral projection; a slidable member carried by the other of said parts, adapted 25 to control the mechanism to be locked, a portion of said member being movable to a co-operative position with said projection to prevent the separation of said casing parts; and means comprising a rotatable disc 30 carried by the first mentioned casing part, for controlling the sliding movements of said member.

ALEXANDER GILCHRIST HATCH.
